SHAVING DEVICE

William S. Sussman, New York, N. Y.

Application October 20, 1939, Serial No. 300,305

9 Claims. (Cl. 30—43.5)

This invention relates to new and useful improvements in mechanical shavers, or shavers with moving blades, and the principal object of the invention is the provision of an improved device of this character having a true shaving action, that is, a cutting action similar to that of a scythe, as distinguished from the clipping or the lawn mower type of shaver having a movable blade and a cooperating stationary blade.

Shavers of the latter type are objectionable for the reason that the stationary cutting element or shear plate must be of sufficient thinness as to render it structurally weak. Furthermore, the success, if any, of such shavers resides in their ability to direct the hairs into these recesses between stationary and moving blades. This can, of course, be done, a few hairs at a time, but the process of shaving is slow and tedious and the result is not a true shaving action but rather a chopping or "guillotine" type of action. Another objection to this general type of razor is in the fact that in the event that the user moves the shaver head faster than the clipping action can be completed, the result is a pulling of the hair from the root.

The action of the present razor is similar to that of an ordinary straight or safety razor when the blade of such razor attacks the hairs at an angle. In other words, in normal shaving the blade is held at some angle other than a right angle to the line of movement of such blade. The present razor cuts in the same manner by providing an elongated, generally cylindrical rotatable cutting element having a spirally disposed cutting edge extending from end to end. This cutting edge is disposed at an angle of between 20° to 30° to a line drawn transversely of the elongated cutting element. As this element rotates, it cuts along a line extending from end to end of the cutter and as the cutter is moved over the face an area the width of the cutter is shaved.

In a slightly modified form of the invention, substantially the same cutter is employed, although it is not given a complete revolution but is rather moved, by the action of a special cam, in the path of an ellipse and the cutting action is substantially the same.

In each instance, the cutter is enclosed within a guard having a longitudinal recess of appropriate width, either toothed or straight edged, such guard preventing injury to the user although the opposed edges do not function in any manner as a stationary cutting blade, since none is necessary.

Another object of the invention is the provision of an improved spiral or helical cutting element so formed in transverse section as to give the edge a maximum cutting action.

A further object of the invention is the provision of a novel type of cutting element so formed as to be capable of excellent shaving results while operating at a relatively slower speed than conventional cutters operate, thus making a spring motor contained within the handle suitable for operating the razor.

Another object of the invention is to provide a mechanical razor capable of cutting the hairs at the base thereof, such razor being adapted for use either with or without the previous application of lather or other preparation to the face.

Yet another object of the invention is the provision of an improved cutting element which may be removed and discarded when dull, and a new one inserted in its place.

In the drawings:

Fig. 1 is a broken, front elevation of the upper end of a motor housing, the view showing a central longitudinal section through the guard or cutter head and a front elevation of the preferred form of cutting element, such section being taken on line 1—1 of Fig. 2;

Fig. 2 is a top plan view of the guard and cutting element, a portion of the former being broken away to show the driving means;

Fig. 3 is a broken transverse vertical section taken on line 3—3 of Fig. 2;

Fig. 4 is an enlarged broken section taken through the cutter guard, such view also showing a broken side elevation of the cutting element;

Fig. 5 is an enlarged transverse section taken through the cutting element;

Fig. 6 is a central longitudinal, horizontal section taken through a head, the view showing a top plan view of the cutting element formed from a piece of tubing rather than from an elongated strip;

Fig. 7 is a top plan view of a modified form of a shaving head;

Fig. 8 is a central, longitudinal section taken through a cutting head, the view showing a side elevation, partially in section of a modified form of cutting element and driving means therefor;

Fig. 9 is a transverse vertical section taken on line 9—9 of Fig. 8; and

Fig. 10 is a plan view of the driving cam.

The structure in Figs. 1 to 5 shows the upper terminal portion 11 of a motor housing, such portion having a semi-circular transverse recess 12

which forms a seat for a cylindrical guard or shaver head 13 within which a rotatable spiral cutting element 14 is positioned.

The motor which is adapted to impart rotative movement to the cutter is not illustrated since it forms no part of the present invention. Any suitable prime mover such as an electric motor or spring motor may be employed, however. Two preferred embodiments of the latter type of motor suitable for such use are disclosed in my co-pending application Serial No. 300,304, filed of even date herewith.

In view of the special construction of the spiral cutter, the drive shaft, designated as 15, is positioned adjacent to one terminal of the guard 13 rather than in the center of the motor housing as is the case in most shavers having traveling blades. The guard may be made from metal or from plastic material and in the arrangement shown it is not centered upon its support, although if a drive is positioned at each end, the guard may be centered on its support. It will be appreciated that any suitable train of gears may be employed to furnish power to the shaft at the side rather than in the center of the motor housing. Also, the housing may, if desired, enclose the full length of such shaft although in the preferred embodiment of the invention a portion of such shaft is not enclosed, as is shown in Fig. 1.

The shaft passes through an aperture 16 in the lower wall of the cylindrical guard and a collar 17 having a set screw 18 is rigidly secured to the shaft immediately below the lower surface of the guard. At the upper end of the shaft a small gear 19 is secured, such gear engaging the teeth of a crown gear 20 frictionally secured within the last convolution of the spiral cutter.

The guard 13 is formed with an eccentric bore 22 running from end to end, such bore being so positioned as to leave a relatively thick lower wall portion 23 and a relatively thin upper wall portion 24, all as shown in Fig. 3. The guard is further formed with a longitudinal recess 26 in the upper wall portion, such recess terminating short of the ends of the guard.

An enlarged transverse section of said recess is shown in Fig. 4, and, although the wall portions 24 are relatively thin (about .015 inch) the opposed edges of the slot or recess 26 are not vertical but rather are tapered as shown at 27.

At the end of the bore opposite from shaft 15 a cap 30 is positioned and secured by means of a set screw 31. A short bearing member 33 is positioned within the last convolution of the spiral cutter and is secured therein by frictional engagement. This bearing member 33, as well as the crown gear 20 may be formed with a slight projection which will fit within a recess in the spiral cutter, such method of more positive securing being illustrated in a subsequent embodiment of the present invention. A bearing pin 35 positioned in the end cap passes through an aperture in the bearing member 33.

The lower wall 23 of the guard is formed with a threaded aperture 38 aligned with another aperture 38 in the upper terminal of the motor housing 11. A set screw 39 positioned in such aperture securely holds the guard in place, the head of such screw lying entirely within a recess 40 in the member 11.

The cutting element is formed in the shape of a spiral and a transverse sectional view of one convolution of such cutting element is shown in Fig. 5. It will be noted that such cutter is thick-

est at its center 42 and tapers down to relatively thin opposed cutting edges 43. This cutting element may be made from steel although such cutter formed from glass has given unusual results. The cutter is desirably formed in a flat elongated strip having the cross-sectional shape of the structure shown in Fig. 5. The opposed edges are then sharpened in the usual manner and the strip cut to suitable length for the cutting element. The strip is then bent to helical shape and the gear 20 and the bearing member inserted in opposite ends thereof. The external diameter of the cutter is such as to fit fairly snugly within the cylindrical guard 13 although it must not have such a large diameter as to bind when positioned within the guard.

It will be noted that the cutting edges 43 lie at an angle of approximately 25° to a line drawn transversely of the cutting element. Such an angle of the cutting edges has been found to give a true shaving action as distinguished from a clipping action or "guillotine" action of the type found in practically every shaver having a traveling cutting element and a cooperating stationary blade.

It will also be apparent from an examination of Fig. 3 that the edges 26 of the recess in the guard have no cutting function whatsoever since such edges are spaced from the cutting edges 43 of the cutter. This invention is not limited, however, to the special shape of cutting element wherein the edges are spaced from the opposed edges of the slot in the guard.

When the cutter is turning at a speed of 500 R. P. M. or thereabouts, all the whiskers in an area the width of the recess 26 are shaved in a scythe-like manner as the shaver is moved over the face at normal shaving speed. As was earlier pointed out, the foregoing device may be used with or without previous application of lather to the face. A suitable pre-torsorial preparation is preferred, however, and during the operation of shaving the lather or other preparation will, as it is removed from the face, pass into the bore in the guard and out the open end at the right (Figs. 1 and 2). If a spring motor of the type described in my co-pending application, instead of an electric motor, is employed to rotate shaft 15, a safety factor of high order will be present in the shaving apparatus, since slightly too much pressure of the cutter against the skin will retard or even stop rotation of the cutter. By providing such a safety factor the guard could, if desired, be eliminated entirely. In other words, by forming the cutting element in such a manner as to provide a space between two convolutions substantially equal to the width of each convolution of the cutter, all as clearly shown in Fig. 1, the hairs on the face are presented to the cutting edges for effective removal without danger of cutting the skin. Since the guard structure forms a support for the cutting element, and permits rotation thereof, some such structure must be provided although it need not necessarily be so formed as to function as a guard.

The cutting element 45 shown in Fig. 6 has the same cutting function as the cutter shown in Figs. 1 to 5. This cutter 45 is made from a single tubular piece of metal and cutting edges 46 are formed in any manner well known in the art. Such edges terminate in straight portions 47 which are desirably not sharpened.

The guard 49 shown in Fig. 7 is similar to that shown in Fig. 2 except that the recess, instead

of having straight, parallel, opposed edges, is formed with edges comprising a plurality of spaced teeth 57, the edges of which teeth are substantially parallel with the cutting edges 43 of the cutter 14.

In the modified embodiment shown in Figs. 8 to 10, inclusive, the cutting element is substantially identical with that shown in the preferred embodiment of the invention.

The principal difference between the first and the second embodiments, however, is in the line of movement of cutter. In the former, the cutting element has a straight rotary movement and an end drive is provided to cause such movement. In the second form, however, the cutting element is not given a complete revolution but is rather given a combination of reciprocating and oscillating movements.

The drive in this instance is a center drive rather than an end drive, and is furnished by a central vertical shaft 51 journalled within a bearing member 52 which is rigidly secured within the upper end of a frame. The frame has a reduced portion 54 at its upper end which is threaded and forms a seat 55 for the upper end of a motor housing 56. The motor may be of the spring type disclosed in my co-pending application or it may be a conventional electric motor.

A circular nut 58 is carried on the threaded portion, such nut having a semi-circular recess 59 which forms a seat for the elongated cylindrical guard 60. This guard is likewise provided with an eccentric longitudinal bore 61 leaving a relatively thick lower wall 62 and a relatively thin upper wall 63. The lower wall is provided with a threaded aperture 64 which receives the upper threaded portion of the bearing member 52. The cutting element comprises a spiral cutter 66 constructed in the same manner as the cutter 14 in the preferred embodiment and a core 67 which is cylindrical in shape, is made from solid material such as metal or plastic and is formed with a spiral recess 68 corresponding to the voids between the cutter edges of the cutter 66. This recess 68 is concavely curved in transverse section as shown in Fig. 8. At each end of the core a small projection 69 is formed, which projection is fitted within a recess 70 adjacent to the end of the cutter. It will be apparent that such cutter may be readily slipped off the core when a new cutter is to be employed.

One end of the guard may, if desired, be provided with a cap and such cap may be provided with a bearing member passing into a longitudinal aperture in the core 67 although this is not normally necessary. The guard is further formed with a longitudinal opening 71 along the upper edge thereof.

The lower surface of the core is formed with an aperture 78 within which is positioned a circular cam 79 which is secured eccentrically of the drive shaft 51 at the upper end thereof, the cam being of only slightly smaller diameter than the diameter of the aperture 78. To describe the movement of the cutter when viewed from the position shown in Figs. 8 and 9, assume the drive shaft 51 to be rotating in a counterclockwise direction and the cam has first moved the cutter to its maximum position to the left in Fig. 8. Further rotation of the cam causes the cutter to describe an arc in the direction of the right in Fig. 9 and continued rotation causes it to further continue its arcuate movement to its maximum position to the right in Fig. 8, thence to the left in Fig. 9 and back to starting position.

In other words, each point on the cutter traverses a path in the nature of an ellipse or flattened circle.

Any other type of internal support for the cutter 66 may be provided and such support may be a skeleton framework, if desired. Also, if formed as shown in Fig. 8 the recesses 68 may be made considerably deeper and a longitudinal bore may be formed in the core in order to aid in the removal of the hairs as they are cut by the razor.

Both embodiments may be modified considerably without departing from the spirit of the invention, as defined by the appended claims. For instance, the opening in the guard in each instance may be placed on the side rather than in the top thereof.

What I claim is:

1. A mechanical razor comprising a movable cutting element, a guard formed with a longitudinal bore, the cutting element being positioned within said bore, and means for imparting movement to said cutting element, said element consisting of a helical member formed in transverse section with a thickened portion tapering down to a cutting edge, the guard having a longitudinal slot therein, the cutting edge lying out of contact with the bore in the guard.

30 2. A mechanical razor comprising a movable cutting element, a guard formed with a bore from end to end enclosing the cutting element and means for imparting movement to said cutting element comprising a prime mover operatively connected with the cutting element, said element consisting of a helical member formed in transverse section with a thickened portion tapering down to a sharpened cutting edge lying inside the outer periphery of the thickened portion, the guard having a longitudinal slot therein, the cutting edge lying out of contact with the bore in the guard.

35 3. A mechanical razor comprising a rotatable cutting element, a guard formed with a longitudinal bore enclosing the cutting element and means for imparting movement thereto, said cutting element comprising a helical member formed in transverse section with a thickened central portion tapering down to a cutting edge, the guard having a longitudinal slot therein, the cutting edge lying out of contact with the bore in the guard, and means comprising a prime mover operatively connected with one end of the cutting element for imparting rotative movement thereto.

40 4. A mechanical razor comprising a movable cutting element consisting of a helical member formed in transverse section with a thickened central portion tapering down to cutting edges on opposite sides thereof, a support for the cutting element comprising a handle portion, a substantially cylindrical guard member having a longitudinal bore and a longitudinal slot therein secured to said handle portion, the cutting element positioned within said bore, the cutting edges of the helical member lying inside the outer periphery of the central portion and out of contact with the bore in the guard.

45 5. A mechanical razor comprising a rotatable cutting element and a substantially cylindrical guard having a longitudinal bore therein, enclosing said cutting element, said element comprising a helical member formed in transverse section with a thickened body portion which tapers down to a sharpened cutting edge, the guard having a longitudinally disposed slot therein ex-

posing a portion of said cutting edge at each convolution of the helical member, the exposed portion of the cutting edge throughout its length lying inside of, and out of contact with, the bore of the guard, and means comprising a prime 5 mover for imparting rotation to the cutting member.

6. A mechanical razor comprising a movable cutting element and a support therefor, said element including a helical member formed with a thickened portion tapering down to a sharpened cutting edge, said edge, throughout its 10 length, lying inside the outer periphery of the thickened portion, and means for imparting movement to the cutting element comprising a prime mover operatively connected with the element.

7. A mechanical razor comprising a rotatable cutting element and a substantially cylindrical guard having a longitudinal bore therein, enclosing said cutting element, said element comprising a helical member formed in transverse section with a thickened body portion which tapers down to a sharpened cutting edge, the guard having a longitudinal slot therein exposing a portion of said cutting edge at each convolution of the helical member, the cutting edge lying inside, and out of contact with, the bore of the guard, a handle supporting the guard, and means comprising a prime mover positioned with 25 the handle for imparting rotation to the cutting member, a gear secured at one end of the helical

element and means connecting the prime mover and the gear.

8. A mechanical razor comprising a substantially cylindrical guard having a longitudinal bore therein, a helical cutting element journaled within the bore for rotative movement, a gear secured at one end of the cutting element, a prime mover connected with said gear to impart rotative movement to the helical element, the guard having a longitudinally disposed opening extending substantially the full length thereof and exposing a plurality of convolutions of the helical element, each convolution of said element being formed with a thickened portion tapering down to a sharpened cutting edge lying out of contact with the bore.

9. A mechanical razor comprising a helical cutting element, a support therefor and means including a prime mover for imparting rotation thereto, said cutting element being formed in transverse section with a portion which tapers down to a sharpened cutting edge, such cutting edge lying inside the outer periphery of the helical element, the width of such transverse section being substantially the same as the distance between two convolutions of the cutting element, whereby a plurality of adjacent convolutions, when pressed into contact with the skin, form ridges thereon and thus present the hairs for effective removal by the cutting edge.

WILLIAM S. SUSSMAN.
